DESIGN FOR A SCATTER RUG OR SIMILAR ARTICLE OF MANUFACTURE

Albert D. Clist, Purdy, N. Y., assignor to Wollner-Clist Inc., New York, N. Y., a corporation of New York

Application December 29, 1945, Serial No. 125,156

Term of patent 7 years

(Cl. D92—21)

To all whom it may concern:

Be it known that I, Albert D. Clist, a citizen of the United States of America, and resident of Purdy, county of Putnam, and State of New York, have invented a new, original, and ornamental Design for a Scatter Rug or Similar Article of Manufacture, of which the following is a specification, reference being had to the accompanying drawing, forming a part thereof.

In the drawing, Fig. 1 is a face view of a scatter rug embodying my design, and Fig. 2 is a side view thereof.

I claim:

The ornamental design for a scatter rug or similar article of manufacture, as shown.

ALBERT D. CLIST.
